THREAD CONTROLLING MECHANISM

Rudolf Abrams, Bechtelsville, Pa.

Application July 13, 1938, Serial No. 218,991

7 Claims. (Cl. 66—146)

The present invention refers to yarn clamping and let-off devices such as are used in knitting machines or other textile machinery. The invention is especially adapted for use in knitting machines for taking up fine yarns which are fed intermittently and for clamping them except at such times as they are fed to the knitting instrumentalities of the machine.

In the figures of drawings:

Fig. 1 is an elevation showing the invention as applied to wrapping mechanism on a typical knitting machine;

Fig. 2 is a section taken through a part of Fig. 1 and showing one take-up and let-off device to an enlarged scale;

Fig. 3 is a section showing a fragment of the device and illustrating one take-up and let-off assembly as seen from above;

Fig. 4 is a section showing in detail the manner in which a yarn is to be clamped or held by the device;

Fig. 5 is a detail showing the manner in which the yarn is threaded.

The case presents certain improvements over the mechanism shown and patented in Patent 2,091,407 to Robert H. Lawson. In the feeding of certain yarns, especially yarns for wrap striping, some difficulties have been experienced with the let-off mechanism of said Lawson patent in that there would not be a sufficient clamping action especially after the device had been used for a considerable period of time. With wiry yarns and stiff, rough yarns such as spun artificial filaments, there has been a tendency to groove the clamping surfaces so that after a period of time the yarn would run through the groove or grooves and would not be properly held. Further, in certain instances, more clamping action is desired than is possible in said mechanism of the Lawson patent although that mechanism serves very well for a great many types of yarns and/or filaments.

Now referring to the figures of drawings wherein mechanism has been shown as applied to a wrapping mechanism for hosiery machines, I will describe the specific details and function of one preferred embodiment of the invention. This particular embodiment applies to wrapping mechanism such as used in Banner machines and illustrated in Lawson et al. Patent 1,702,608. While the mechanism is particularly adapted for use in such wrapping devices, it may be used in wrapping mechanisms of other types, and further, is well adapted for use in any knitting machines or other textile machines wherein yarns

or filaments are to be fed by methods similar to those herein disclosed.

The wrapping mechanism includes such elements as a spindle 1 and a bracket 2 supported on a post 3 which extends upwardly from the so-called circular base of the machine. With this type of wrapping mechanism rotation of the wrapping devices which cooperate with the needles as well as the wrap yarn supplies is contemplated. However, the invention is equally applicable to stationary cylinder machines wherein these elements would not be rotated but would be caused to function by other elements rotating with respect thereto. Here the spindle 1 is rotated by gearing (not shown) or in any other suitable way. The spindle also carries a sleeve 4, a plate 5 upon which are mounted a plurality of wrap yarn supplies 6 carried on suitable pins or holders 7. The number of wrap yarn supplies will vary in accordance with the type of machine and other considerations. On a second plate 8 which is fixed at the upper end of sleeve 4, as illustrated in greater detail in Fig. 2, are attached a plurality of let-off devices, one for each of the yarn supplies. At the topmost portion of spindle 1 a second sleeve 9 is fixed by a hub 10 which engages over a flange 11 on the sleeve and clamps the same downwardly against plate 8. This hub 10 is slotted radially as at 12 and also circumferentially at 13. A wire 14 fits within the circumferential slot or groove 13 and serves as a pivot for a plurality of take-up arms 15 which serve to take up the slack in their respective wrap yarns and for another purpose to be described in greater detail as this disclosure progresses. The groove or slot 13 is undercut at the lower outer edge so that the wire 14 will spring outwardly and be locked in place once the assembly has been completed. Each of the take-up arms 15 has a spring 16 attached as illustrated, this spring also being held by a hook 17 adjustably retained as by a set screw 18 within a flanged collar 19 at the upper end of the sleeve 9. These hooks 17 may be adjusted to increase or decrease the tension in the springs 16 and thereby to induce different take-up actions in accordance with the particular yarn size, material, etc.

Adjacent the outer or free end of each take-up arm 15, I provide an eyelet 20 passing through the plate 8 and through which the yarn or filament may be passed as it is carried downwardly to the knitting point. Similar eyelets will be provided in the plate 5. A plurality of arcuate wires 21 are to be fixed in plate 8 just outside the ring

or eyelet 20 and the yarn or filament will be passed beneath this wire 21, upwardly through an eyelet 22 in the end of take-up arm 15, then downwardly through the eyelet 20.

Substantially in radial alignment with each of these take-up arms 15, I provide a yarn clamp and let-off device comprising certain new and useful features. A post 23 which has been constructed of a piece of square stock turned down for a part of its length serves to clamp a U-shaped thread guiding element 24 in position as said post is maintained in position by the nut 25. The upper square section of said post is slotted and an arm or lever 26 having an outer curved portion 27 is freely pivoted on a pin 28. This arm or lever 26 extends inwardly of the machine to terminate in an off-set or angularly bent part 29 which engages beneath the lever or arm 15. A block 30 which serves as a movable clamping element is pivoted on a pin 31 at the lower end of said curved part 27 of the lever 26. This block 30 is slotted as shown in Figs. 3 and 4 and the lower curved end of said lever 26 engages within said slot. The clamping side of block 30 is curved to an arc of a radius less than the radius of the circular part of the post 23. This assures that there will be a stronger clamping action as illustrated in Fig. 4. The block 30 pivots at the pin 31 so that the pressure of the block will tend to be equalized as it engages post 23, that is, it will press against the post with a more or less equal force from top to bottom, and will also accommodate itself to different clamping positions as it would have to for different sizes of yarn, or in case of lint or dirt lodging beneath it.

The U-shaped element 24 has three holes drilled at either side as indicated at 32. There may be more or fewer of these openings although three has been found to be a suitable number. The thread or filament as it is drawn up from the supply 6 passes through an eyelet 33, then is threaded through the openings 32 from one side to the other and passes behind the post 23, or between the post 23 and the block 30. For different types of yarn it has been found desirable to vary the number of passes of yarn between the clamping elements; for some types it may be suitable to pass the yarn from one side to the other, other yarns may require two or three passes in order to realize suitable clamping and let-off action. In the particular illustration the yarn is passed through twice and is then led under the wire 21, through eyelet 22 and then down through other guiding openings to the wrapping and knitting instrumentalities. I refer to the yarn thus threaded as being passed a plurality of times through the clamping means.

A spring 34 attaches through a hole about mid-way of the arm 26 and again to an extension 35 fixed within the slot at the upper end of post 23. Several holes are provided in both the arm and the extension so that different springs may be adjusted to any desired tension by changing from one set of holes to another. When the arm 26 is not being held downwardly thereby extending spring 34 as in Fig. 2, the said spring will pull the arm upwardly and about pivot 28 swinging the block 30 inwardly against the yarns passing between it and post 23. This will cause the yarn to be clamped until such time as arm 26 is moved downwardly against the tension of spring 34 whereupon the clamping block 30 will be moved away from the post and the yarns themselves. At that time the yarns will be drawn freely

through the various eyelets and openings through which they are threaded.

Summing up the operation briefly, the yarn is threaded through the eyelet 33 and through a suitable number of the openings 32 as described, then under wire 21 through the eyelet 22 at the free end of take-up arm 15 and thence to the knitting point. If the take-up arm 15 is in any position from that illustrated in Fig. 1, to a position wherein it just engages the offset end 29 of arm 26, the clamp 30 will be held against the yarn by spring 34 as aforesaid. As the yarn is taken and is drawn downwardly through eyelet 20, the take-up arm 15 will be pulled downwardly against the tension of spring 16 until it engages the offset end 29, any further movement of that arm 15 then swinging the longer arm 26 about pivot 28 and extending spring 34. A slight movement of the arm 26 will withdraw the block 30 sufficiently to release the clamped yarn. Due to the compound system of levers, it takes very little tension within the yarn to release the clamp 30. As long as the yarn is feeding steadily, arms 15 and 26 will be held as in Fig. 2 and the yarn will be drawn freely through the various eyelets and openings. Just as soon as the yarn is not being taken, or as soon as the same becomes slack, the take-up arm 15 will move upwardly, the clamp 30 will engage and hold the yarn passing through the openings 32 and no yarn will then be possible of drawing from the supply. There is sufficient movement of the take-up arm 15 after the clamp has engaged the yarn as just described, to serve the usual take-up purpose for keeping slack out of a wrap or other yarn. This function is well known with respect to wrap stripe knitting machines.

The invention has been described with respect to one specific embodiment, but changes will be apparent to those skilled in the art and the disclosure contemplates such changes without departing from the scope of the invention as originally conceived. The invention is defined in the appended claims.

45 I claim:

1. A yarn clamping and let-off device of the type described including fixed and movable clamping elements, guiding means for guiding a yarn between said fixed and movable elements 50 having a plurality of openings so that said yarn may be passed between the elements a plurality of times.

2. A yarn clamping and let-off device including a fixed and a movable clamping member, guiding means at either side of said clamping members having a plurality of yarn guiding openings, said openings being adapted to guide a yarn between said members a plurality of times.

60 3. Yarn clamping and let-off means including a post, part of said post being adapted for the clamping of a yarn, a movable member for engaging the clamping portion of said post and a lever pivotable within said post and also pivotally carrying said movable clamping member, and yarn guiding means at either side of said post provided with a plurality of openings whereby a yarn may be passed a plurality of times between said post and the movable clamping member.

70 4. Yarn clamping and let-off means including a post having a portion thereof of circular cross section, guiding means for guiding a yarn to be passed one side of said post a plurality of times and adjacent said circular part thereof, and a

movable clamping member adapted to engage the yarn at said circular part of the post, the clamping portion of said member being formed to an arc of lesser radius than the radius of said circular part of the post.

5. Yarn clamping and let-off means of the type described including a post, part of said post being circular in cross-section and the upper portion therefor being slotted, a lever pivoted within said slot and having a curved, depending end, a movable clamping element pivoted at said curved end, spring means for drawing said lever in a direction to press said clamping member against the circular section of said post, and guiding means adapted to guide a yarn between said post and clamping member a plurality of times.

6. Yarn clamping and let-off means including a post having a portion thereof circular in cross-

section, guiding means for guiding a yarn to pass one side of said post a plurality of times and adjacent said portion of circular cross-section, a movable clamping member adapted to engage the yarn at that part of the post, said clamping member having a clamping surface so constructed as to engage the circular cross-section of the post along two independent spaced lines of contact.

7. Yarn clamping and let-off means for machines of the type described including a fixed clamping member, a movable clamping member and guiding means for guiding a yarn to pass to and fro a plurality of times between said fixed and movable members, the said movable member being mounted to pivot freely and in such a manner as to be self-aligning in its clamping action against the fixed member.

RUDOLF ABRAMS.
